SHOCKPROOF SWITCH

Joseph W. McClain, Schenectady, N. Y., assignor
to General Electric Company, a corporation of
New York

Application September 2, 1944, Serial No. 552,406

2 Claims. (Cl. 200—111)

1

My invention relates to shockproof switches, more particularly to shockproof electromagnetically operated switches, and has for its object a simple, reliable and inexpensive switch in which the moving parts are statically balanced so as to be free from the effects of shocks.

In carrying out my invention in one form, I provide a disc shaped member mounted for rotation on a central axis about which the disc is statically balanced. One half of the disc is in the form of a peripheral strip or bar which has at one end a portion made of magnetic material, the remainder of the strip and the disc being made of non-magnetic material. I further provide an operating coil surrounding the strip which, when energized, pulls the magnetic strip portion into an attracted position whereby the disc is rotated and switch means connected to the disc is moved between its operating positions.

For a more complete understanding of my invention, reference should be had to the accompanying drawing, the single figure of which is a diagrammatic representation of an electric switch embodying my invention.

Referring to the drawing, in one form of my invention I provide a circular or disc-like member 1 which may be formed or cut from a plate of non-magnetic material, such as brass or a phenolic compound. One half of the disc 1 is formed or cut away to leave a large aperture 2 and a semicircular peripheral strip or bar 3. The strip 3, furthermore, is provided at one end with a portion 4 made of magnetic material which extends throughout substantially one half the length of the strip.

The disc 1 is mounted for rotation on a pivot shaft 5 at its center, about which pivot shaft 5 the disc is statically balanced. This static balance, for example, may be obtained by adding suitable material if required to the strip 3 to offset the greater weight of the opposite solid half of the disc.

To effect the rotation of the disc through a substantially 90-degree angle thereby to operate an electric switch 6, I provide a stationary operating coil 7 which surrounds the strip 3. Preferably, the coil is provided with a central bore 8 which is large enough to accommodate substantially one half of the length of the strip 3, the coil having a length sufficient to extend over substantially one half of the length of the strip 3. By means of suitable biasing means, such as a spring 9, the disc 1 is biased to an angular position in which the non-magnetic portion of the strip 3 extends through the coil. When the coil is energized, the

2

magnetic portion 4 is pulled into the coil and the disc thereby rotated substantially 90 degrees in a clockwise direction, as seen in the drawing.

Preferably, as shown, the movable part of the switch 6 is mounted on one end of a bell crank 10, the opposite end of which is connected by means of a link 11 to a pivot 12 secured to the disc 1 a suitable distance from the pivot 5. As shown, the pivot 12 is in such a position that it lies on a radius extending substantially at right angles with the link 11. Therefore, when the disc is rotated clockwise to its attracted position, the pivot 12, in moving through a 90-degree angle, moves downward below the pivot shaft 5 into a dead center position, i. e. parallel with a radius of the disc, with respect to any force applied by the link 11 to the disc and switch. This rotation of the disc, it will be observed, moves the switch to its closed circuit position. Thus the disc itself is not only statically balanced about its pivot shaft 5, and therefore free from the effects of shocks, but the disc is not affected in terms of rotation by any shock or other force applied to the disc by the switch. This is because any such force is applied directly to the shaft 5 without any component producing rotation of the disc in either direction.

If desired, suitable stop means may be provided for limiting the rotation of the disc in each direction, especially stop means for positioning the disc angularly in its attracted position so that the link 11 extends along a radius of the disc. As shown, the inner side 13 serves as a stop by engagement with the upper end of the coil to limit the counterclockwise rotation of the disc by the biasing spring 9, while the similar inner side 14 of the disc engages the lower end of the coil to limit the clockwise rotation of the disc by the coil.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

1. A shockproof switch comprising a disc member made of non-magnetic material provided with a substantially semi-circular strip defining one half of the disc member, a portion of said strip being made of magnetic material, a central pivot for said disc member about which said disc member is statically balanced, a coil surrounding said strip, means biasing said disc member to a position in which the non-magnetic portion of said strip extends through said coil whereby when said coil is energized said disc member is

rotated substantially 90 degrees thereby to bring said magnetic portion of said strip into an attracted position with respect to said coil, circuit control means, a link connecting said circuit control means with said disc member, said link being connected to a pivot on said disc member in such position that when said disc member is in said attracted position said link lies along a radius of said disc member whereby a force applied by said link to said disc member is ineffective to produce rotation of said disc member.

2. A shockproof switch comprising a disc member made of non-magnetic material having a substantially solid semi-circular portion and a peripheral strip defining the opposite half of the disc, substantially one half of said strip being made of magnetic material, a central pivot for said disc about which said disc is statically bal-

anced, a coil surrounding said strip and coextensive with substantially one half of the length of said strip, means biasing said disc to a position in which said non-magnetic half of said strip extends through said coil whereby when said coil is energized said disc is rotated substantially 90 degrees thereby to bring said magnetic portion of said strip into an attracted position inside of said coil, circuit control means, a link connecting said circuit control means with said disc, said link being connected to a pivot on said disc in such position that when said disc is in said attracted position said link lies along a radius of said disc whereby a force applied by said link to said disc member is ineffective to produce rotation of said disc member.
